UNITED STATES PATENT OFFICE.

ANDREW M. STEWART, OF TOLEDO, OHIO, ASSIGNOR TO THE NATIONAL SUPPLY COMPANY, OF TOLEDO, OHIO, A CORPORATION OF OHIO.

COMBINATION SUCKER-ROD SOCKET.

1,123,615.

Specification of Letters Patent.

Patented Jan. 5, 1915.

Application filed July 30, 1913. Serial No. 781,976.

To all whom it may concern:

Be it known that I, ANDREW M. STEWART, a citizen of the United States, residing at Toledo, in the county of Lucas and State of Ohio, have invented new and useful Improvements in Combination Sucker-Rod Sockets, of which the following is a specification.

My invention relates to slip-sockets for sucker-rods and its object is to provide slip-sockets with slips constructed to catch a sucker-rod pin when a joint has become unscrewed, and also to catch the rod below the pin when the rod breaks, that is, its object is to provide slips which will catch rods or other articles of different diameters without requiring the slips to be exchanged for others of a different size.

Referring to the accompanying drawing, Figure 1 is a longitudinal section showing a pin gripped by the lower portion of the slips, and Fig. 2 is a similar section showing a rod of smaller diameter gripped by the upper portion of the slips.

On the drawings, 1 represents the bowl of the slip-socket provided at the upper end with the sub or pin member 2, and at its lower end with the set of internal slips 3, tapered downwardly to correspond with the taper or downward convergence of the inner wall of the bowl. The slips are pressed downwardly by the spring 4 confined between the member 2 and the flanged washer 5 on the upper ends of the slips.

The slips have their upper ends curved internally on arcs of one radius, and their lower portions curved internally on arcs

of a larger radius, the two portions having their internal walls parallel and being connected by the upwardly and inwardly inclined guide or shoulder 6. Each portion is provided with transverse teeth, preferably pointing slightly upward.

It is seen that the lower portion of the slips are constructed to receive and grab the rod or pin 7 of a certain diameter while the upper portion can grab the rod 8 having a smaller diameter, the washer 5 permitting the rod to extend up into the spring 4. By my improved slip-socket the same set of slips will catch a sucker-rod pin when it unscrews, or will catch a smaller rod when it breaks. Of course, the lower portion of the slips may catch rods having the proper diameters. By screwing out the sub 2, the spring, the washer, and the slips may be removed so that slips of a different size or character may be inserted in the bowl.

I claim—

In a slip-socket, a set of slips having one gripping portion inclosing an opening of one size and a lower gripping portion inclosing an opening of a larger size, the walls of the openings in the said two portions being parallel the two portions being in axial alignment and connected by a guide wall tapering from the larger to the smaller opening.

Signed at Toledo, O., this 25th day of July, A. D. 1913.

ANDREW M. STEWART.
